(57) **CLAIM**

The ornamental design for a rifle barrel, as shown and described.

DESCRIPTION

FIG. 1 is a perspective view of a rifle barrel showing the new design.

FIG. 2 is a partial perspective view of a rifle barrel showing the new design.

FIG. 3 is a front view of a rifle barrel showing the new design.

FIG. 4 is a rear view of a rifle barrel showing the new design.

FIG. 5 is a top view of a rifle barrel showing the new design.

FIG. 6 is a bottom view of a rifle barrel showing the new design.

FIG. 7 is a first side view of a rifle barrel showing the new design; and,

FIG. 8 is a second side view of a rifle barrel showing the new design.

The broken lines in the drawings are for environment only and form no part of the claimed design.
